J. B. DAUDELIN

SHUTTLE

Filed April 9, 1927

UNITED STATES PATENT OFFICE.

JEAN B. DAUDELIN, OF FALL RIVER, MASSACHUSETTS.

SHUTTLE.

Application filed April 9, 1927. Serial No. 182,252.

This invention relates to new and useful improvements in shuttles and more particularly to means for threading the shuttle and for guiding and maintaining the thread in proper position both before and after threading during its passage from the bobbin to the delivery eye of the shuttle.

The prior art discloses many attempts to provide satisfactory means to maintain the thread within the shuttle throat during the run of the shuttle and to avoid "ballooning" or escape of the thread from the shuttle while the thread is slack. Various arrangements and shapings of the shuttle throat have been attempted, and metal, wooden and vitreous shuttle guide eyes or thread conductors have been introduced into the shuttle. These devices have assumed many varyingly complicated forms and in some cases have been of considerable weight.

In my present invention I provide a shuttle guide eye or thread conductor which defines the path of travel of the thread and prevents escape of the thread from its proper path as it passes from the bobbin to the delivery eye during the run of the shuttle. My shuttle eye guard or thread conductor consists of a simple suitably shaped piece fitted into the shuttle wall and extending across the shuttle throat, and having a suitable opening for the entry and passage of the thread therethrough.

Shuttles heretofore disclosed in the prior art have also included various forms of threading devices and means for guiding the thread from the threading point through the slots in the shuttle frame to the delivery eye.

In my invention I provide as a single unit a combined threading guard and guide and delivery eye. This unit is so positioned in the shuttle as to ensure quick and efficacious threading, and also serves as a guide for the thread to the point where it rounds the snubbing post at right angles to the longitudinal axis of the shuttle and slips into the delivery eye. Both of these agencies are embodied in a single piece of wire twisted to a form which permits the functions of threading, guiding and delivery to be performed rapidly in turn. This device is suitably set into the shuttle frame and while it may be removed if worn and a new unit installed, this is not generally necessary as the material employed is possessed of great

durability and is not subject to defects resulting from wear.

The threading and guiding equipment for my shuttle is exceedingly simple in construction and obviously inexpensive as compared with structures heretofore employed. A shuttle so equipped avoids that frequently experienced unbalancing which resulted from the great weight of equipment at the operating end of the shuttle.

The construction and operation of my invention will be more fully disclosed in the specification which follows and in the drawings which form a part thereof in which I have shown and illustrated an embodiment which not only discloses the principles involved but which is in itself a form proven to be satisfactory in practice and well adapted to the requirements of manufacture.

Throughout the specification and drawings like reference numerals are correspondingly employed and in these drawings:

Fig. 1 is a plan view partly broken away to show my eye guide and threading and guiding equipment in position in a shuttle.

Fig. 2 is a view of my eye guide in place in a shuttle.

Fig. 3 is a section on the line 3—3 of Fig. 1.

Fig. 4 is a detail view of the eye guide or thread conductor; and

Fig. 5 is a view of my unitary threading, guiding and delivery device.

The shuttle body 1 may be of usual construction having a bobbin chamber 2 in which is located a bobbin 3 on which is wound a thread T. The forward end of the bobbin chamber opens up into a throat so shaped as to provide an overhang 5 for the thread passage 6 from which leads laterally the thread delivery opening 7. Exactly opposite, the delivery opening 7 the shuttle body is cylindrically bored to provide a passageway 8 for one end of my unitary guide and eye guard 20 as will be explained hereinafter.

The shuttle body is cut and sawed as usual to provide threading slots 9 and 10. The slot 9 is disposed diagonally of the longitudinal axis of the shuttle and opens into the thread delivery eye 7. The longitudinal slot 10 extends from the point of juncture with the slot 9 past the delivery opening 7 to the end of the bobbin chamber 2.

Just back of the bobbin chamber 2 the

shuttle wall is counterbored at 11 to receive my eye guide or thread conductor 12. In the form shown in the drawings, this conductor consists of a device of general 5 clothespin design, one shank 12' being somewhat longer than the other, and of slightly larger diameter and having a flat end 12¹; the other shank 12² is somewhat shorter and is beveled on its upper inner face at 12⁴ to 10 permit easy and unobstructed passage of the thread thereover. Between the shanks is a recess or guideway 12⁵ in which the thread travels on its way from the bobbin to the eye. This conductor is positioned in the 15 bore 11, so that its shanks extend through the recess beneath the overhang 5 and enter a counterbore 13 in the shuttle body in alignment with the bore 11. The longer shank 12' extends to the entire depth of the 20 bore 13 but between the shorter shank 12² and the overhang 5 there is just sufficient space to permit easy clearance for the thread over the shank 12² into the guideway 12⁵.

I will now describe my unitary threading 25 guide and delivery eye. This comprises a single length of wire 20 and is so shaped at one end as to define a thread delivery eye 20' adapted to be fitted within the delivery opening 7 in the shuttle wall; and at its opposite end 20² acts as a guide or guard over which the thread is slipped and which guides the thread in threading the shuttle in its passage through the slots 9 and 10 hence to the delivery eye 20' seated in the 35 delivery opening 7. This unitary device has an extended shank 20³ which enters and is firmly held in the bore 8 of the shuttle wall. Inwardly of the eye 20', the shank 20³ is bent upon itself as indicated at 20⁴ to provide a 40 barrier effective to prevent escape of the thread from the eye of the shuttle after threading of the shuttle. This barrier 20⁴ is also effective to guide the thread from the bobbin in its passage through the opening 7 45 to the metal eye 20'.

It will be noted (Fig. 3) that the bore 8 for the unitary guard and delivery eye and the bore 13 for the shanks of the thread conductor 12 overlap. This overlapping avoids 50 any necessity for sawing or cutting a passageway for the thread from the bore 13 to the snubbing post 14 which is located transversely of the shuttle midway of the bore 8 and directly in line with the thread delivery opening 7 and the metal eye 20' inserted therein.

In threading my shuttle, the thread is carried straight forward from the bobbin 3 and slipped over the extreme end 20² of 60 the thread guard 20. It is then pulled back through the slot 9 until it slips into the other end 20' of the guide 20 which is seated in the delivery opening 7 of the shuttle wall. As the thread rounds the post 14 it is 65 directed to the right just enough to cause it

to slip over the short shank 12² of the clothespin thread conductor into the guideway 12⁵ through which it continues to travel so long as the shuttle is in use. Once the shuttle is threaded and the thread is in the 70 recess 12⁵ and the eye 20² it is practically impossible to unthread the same without breaking the thread; nor is there any chance of the thread jumping out of its predetermined path of travel within the conductor 75 12 in case the shuttle is at rest and the thread slack.

Various modifications may be made in the construction of my thread conductor; and its position in the throat of the shuttle 80 and with relation to the delivery eye obviously may be varied. The construction and curvature of the thread guide and wire delivery eye may also be varied in order to adapt the same to the contour of the threaded slots, and other modifications in the form and construction of the device 85 may be made without departing from the spirit of my invention if within the limits of the appended claims.

What I therefore claim and desire to secure by Letters Patent is:

1. In a shuttle having a throat, and a thread delivery eye, a bore intersecting said throat, a thread conductor comprising a unitary slotted device of general clothespin design, one shank being shorter than the other, said conductor disposed in said bore with said shorter shank uppermost, a space between said shank and the wall of said bore to permit the thread to slip over said shank and pass through said slot in its travel from the bobbin to the thread delivery eye, a second bore intersecting said throat and providing a thread delivery opening, said bores overlapping to afford a connecting passage for the thread from the conductor to the delivery opening, a thread guard and guide mounted in said second bore and effective initially to guide the thread through said slot into said delivery opening and subsequently to prevent escape of the thread by direct upward lifting movement during the run of the shuttle.

2. In a shuttle having a throat and a thread delivery eye, the shuttle wall adjacent said throat being shaped to define an overhang for a portion of said throat, a bore intersecting said throat, a thread conductor comprising a unitary slotted device of general clothespin design, one shank being shorter than the other, said conductor disposed in said bore with said shorter shank uppermost, a space between said shank and the wall of said bore to permit the thread to slip over said shank and pass through said slot in its travel from the bobbin to the thread delivery eye, a second bore intersecting said throat and also beneath said overhang and providing a thread delivery open-

- ing, said bores overlapping to afford a connecting passage for the thread from the conductor to the delivery opening, a thread guard and guide mounted in said second bore and effective initially to guide the thread through said slot into said delivery opening and subsequently to prevent escape of the thread by direct upward lifting movement during the run of the shuttle.
- 5 3. In a shuttle having a throat and a thread delivery eye, the shuttle wall adjacent said throat being shaped to define an overhang for a portion of said throat, a bore intersecting said throat, a thread conductor comprising a unitary slotted device of general clothespin design, one shank being shorter than the other, said conductor disposed in said bore with said shorter shank uppermost, a space between said shank and 10 the wall of said bore to permit the thread to slip over said shank and pass through said slot in its travel from the bobbin to the thread delivery eye, a second bore intersecting said throat and also beneath said overhang and providing a thread delivery opening, said bores overlapping to afford a connecting passage for the thread from the conductor to the delivery opening, a thread guard and guide mounted in said second bore and effective initially to guide the thread through said slot into said delivery opening and subsequently to prevent escape of the thread by direct upward lifting movement during the run of the shuttle, and a snubbing post disposed against the inner end of the eye and between it and the thread guide.
- 15 4. In a shuttle having a throat and a thread delivery eye, a slotted thread conductor spaced from the shuttle wall to permit the thread to pass into and through said slot in its travel from the bobbin to the thread delivery eye; a thread guide and guard mounted in said delivery eye and effective initially to guide the thread through said slot into said delivery opening and subsequently to prevent escape of the thread by direct upward lifting movement during the run of the shuttle.
- 20 5. In a shuttle having a throat and a thread delivery eye, a slotted thread conductor spaced from the shuttle wall to permit the thread to pass into and through said slot in its travel from the bobbin to the thread delivery eye; a thread guide and guard mounted in said delivery eye and effective initially to guide the thread through said slot into said delivery opening and subsequently to prevent escape of the thread by direct upward lifting movement during the run of the shuttle, and a snubbing post disposed against the inner end of the eye and between it and the thread guide.
- 25 6. In a shuttle having a throat and a thread delivery eye, the shuttle wall adjacent said throat being shaped to define an overhang for a portion of said throat, a slotted thread conductor disposed beneath said overhang, and spaced from the shuttle wall beneath said overhang to permit the thread to pass into and through said slot in its travel from the bobbin to the thread delivery eye, a thread guide and guard mounted in said delivery eye and effective initially to guide the thread through said slot into said delivery opening and subsequently to prevent escape of the thread by direct upward lifting movement during the run of the shuttle.
- 30 7. In a shuttle having a throat, and a thread delivery eye, the shuttle wall adjacent said throat being shaped to define an overhang for a portion of said throat, a slotted thread conductor disposed beneath said overhang, and spaced from the shuttle wall beneath said overhang to permit the thread to pass into and through said slot in its travel from the bobbin to the thread delivery eye, a thread guide and guard mounted in said delivery eye and effective initially to guide the thread through said slot into said delivery opening and subsequently to prevent escape of the thread by direct upward lifting movement during the run of the shuttle, and a snubbing post disposed against the inner end of the eye and between it and the thread guide.
- 35 8. In a self threading shuttle, a throat having a transverse bore providing a threading eye, a vertically disposed longitudinal threading kerf extending from said throat across said bore and downwardly inclined rearwardly directed kerf intersecting with said vertical kerf and said eye and forming with said vertical kerf an overhanging nose, a vertical post through said bore and substantially aligned with the bobbin axis, and a wire member having a free end in the forward part of the vertical kerf and extending along the edge of the nose and encircling the outer end of the eye in an inwardly directed spiral of slightly more than 360° and then returned to leave a rearwardly projecting bend, thence across the throat in substantially the plane of the intersection of the rearwardly directed kerf with the transverse eye.
- 40 9. In a self threading shuttle, a throat having a transverse bore providing a threading eye, a vertically disposed longitudinal threading kerf extending from said throat across said bore and a downwardly inclined rearwardly directed kerf intersecting with said vertical kerf and said eye and forming with said vertical kerf an overhanging nose having a groove along its edge adjacent the rearward kerf, a vertical post through said bore and substantially aligned with the bobbin axis, and a wire member having a free end in the forward part of the vertical kerf

and extending along the edge of the nose and partially seated in said groove and encircling the outer end of the eye in an inwardly directed spiral of slightly more than 360° and 5 then returned to leave a rearwardly projecting bend, thence across the throat in substantially the plane of the intersection of the rearwardly directed kerf with the transverse eye.

10 10. In a shuttle, a throat having a transverse bore providing a threading eye, a vertically disposed longitudinal threading kerf extending from said throat across said bore, and a downwardly inclined rearwardly directed kerf intersecting with said vertical kerf and said eye and forming with said vertical kerf an overhanging nose, and a wire member having a free end in the forward part of the vertical kerf and extending 15 along the edge of the nose and encircling the outer end of the eye in an inwardly directed spiral of slightly more than 360° and then returned to leave a rearwardly projecting bend, thence across the throat in substantially 20 the plane of the intersection of the rearwardly directed kerf with the transverse eye.

25 11. In a shuttle, a throat having a threading slot and a transverse bore providing a 30 threading eye, a unitary thread guard and guide having a free end lying adjacent said threading slot, an inwardly directed spiral lying within said eye, and beyond said spiral bent to provide a barrier to guide the thread from the bobbin to the shuttle eye and prevent 35 the escape of the thread from the eye during the run of the shuttle, said member

beyond said barrier extending inwardly through said threading eye and anchored in the wall of the shuttle. 40

12. A thread guide and guard for use with a shuttle having a thread delivery opening and a threading slot connecting the bobbin chamber with the delivery end of the eye, comprising a unitary member having a free end shaped to lie adjacent said threading slot and an inwardly directed spiral, adapted to lie within said delivery opening and defining a delivery eye, and beyond said spiral bent to provide a rearwardly projecting barrier to guide the thread from the bobbin to said opening and prevent the escape of said thread from said eye during the run of the shuttle, and thence extending as a shank adapted to lie within said thread delivery opening and anchored in said shuttle wall. 45 50 55

13. A thread guide and guard for use with a shuttle having a thread delivery opening and a threading slot connecting the bobbin chamber with the delivery end of the eye, comprising a unitary member having a free end shaped to lie adjacent said threading slot and a spiral adapted to lie within said delivery opening and defining a delivery eye, and beyond said spiral bent to provide a 60 barrier to guide the thread from the bobbin to said opening and prevent the escape of said thread from said eye during the run of the shuttle, and thence extending as a shank adapted to lie within said thread delivery 65 70 75 opening and anchored in said shuttle wall.

In testimony whereof I affix my signature.

JEAN B. DAUDELIN.
